(57) **CLAIM**

The ornamental design for an organoid microplate as shown and described.

DESCRIPTION

FIG. 1 is a top perspective view of an organoid microplate showing the new design.

FIG. 2 is a bottom perspective view of the organoid microplate of FIG. 1.

FIG. 3 is a top view of the organoid microplate of FIG. 1. FIG. 4 is a bottom view of the organoid microplate of FIG. 1.

FIG. 5 is a front view of the organoid microplate of FIG. 1. FIG. 6 is a back view of the organoid microplate of FIG. 1. FIG. 7 is a right side view of the organoid microplate of FIG. 1.

FIG. 8 is a left side view of the organoid microplate of FIG. 1; and,

FIG. 9 is a partial enlarged top view of the organoid microplate of FIG. 1. The broken lines depict portions of the organoid microplate that form no part of the claimed design.
